UNITED STATES PATENT OFFICE.

HARRIETTE ENSLEY HODGSON, OF NEW YORK, N. Y.

SWINGING HOBBYHORSE.

Application filed August 6, 1924. Serial No. 730,360.

To all whom it may concern:

Be it known that I, HARRIETTE ENSLEY HODGSON, a citizen of the United States, and resident of New York city, in the county 5 and State of New York, have invented a new and useful Swinging Hobbyhorse, of which the following is a specification.

The object of this invention is to provide a strong, inexpensive, attractive and 10 weather-resisting toy which will give children exercise in the open air and which will be serviceable in comparatively small spaces. Hobbyhorses are a very favorite toy, but are for indoor use on smooth surfaces, and 15 are not adapted for yards or areas and are not designed to withstand sun and rain, the rockers and other parts suffering if exposed to such conditions. The thought that I have had in this invention is to make a 20 hobby-horse for the outdoors, and in doing so I have essentially modified the design of such toys and have applied the principle of the swing. The construction sought has been one involving simple and sturdy elements, capable of being made cheaply in 25 metal, wood, or composition, and by reason of its nature and mode of operation having an especial appeal for children. Accordingly my invention comprises an elongated 30 barrel-like body having rising therefrom the effigy of an animal head, and means for suspending the body in a frame or from some other overhead support to swing lengthwise. This barrel-shaped body is not only cheap 35 to manufacture and sturdy in use but is possessed of a simple and grotesque form calculated to appeal especially to the child mind. In this respect my invention differs from known swinging toys having a horse's 40 head in effigy affixed to a suspended disc seat or bucket seat and also from swing or riding devices shaped in the manner of a horse.

In the accompanying drawings illustrating the invention:

45 Fig. 1 is a side elevation of the toy in a suspension frame;

Fig. 2 is a rear end elevation thereof, the lower portion of the frame being broken away;

50 Fig. 3 is a vertical longitudinal section through the hobby-horse, showing suspension ropes or cables, intermediate portions of which are broken away, arranged for suspending the toy from a tree;

55 Fig. 4 is a cross-section on the line 4—4 of Fig. 3; and

Fig. 5 is a fragmentary sectional view showing the manner of attaching a suspension chain used instead of rope.

The hobby-horse shown in the drawings 60 is a double hobby-horse, the double seating capacity being of great advantage since two children swinging together have much more beneficial enjoyment than one alone. The indoor hobby-horse on rockers is not well 65 adapted for tandem construction, but the simple, straight barrel-like body 2 of my swinging hobby-horse can be made in any length. The body can be made hollow, of galvanized iron, or it may be of wood, com- 70 position, solid, etc.

At longitudinally spaced points effigies of horses' or other animals' heads 3 rise from the body, being either formed separately and fixed to the body, or cast or molded in 75 one piece therewith. The forward head is located somewhat in rear of the front end of the body and the rear head an appropriate distance in front of the rear end. The heads are preferably of a block-like, rectangular, or elementary form such as illustrated, both because it is easy to make and because simple forms are liked by children.

A mane 4 is applied to each head, consisting of a rope passed through an opening in 85 the rear, upper part of the head, doubled, wrapped about at 5 adjacent the head, and the two ends then raveled out up to the wrapping so as to form a flowing mane. A rosette 6 on the side of the head where the 90 mane rope passes through the opening conceals the origin of the mane and contributes greatly to the appearance. Two tails 7 are likewise formed by rope threaded through openings in the body at the rear end, and at 95 a point between the two heads, respectively, the rope being doubled and wrapped adjacent the holes, and the two ends being raveled.

A saddle 8 is provided on the top of the 100 body behind each of the heads. Each saddle has a back 9, which for security should be fixed to the body, but the seat 10 of each saddle may be removable from a recess in the top of the body, so that it may be taken 105 indoors in order that its cushion or cover need not be spoiled.

Transverse openings are formed through the body below each of the saddles, and ropes 110 are passed through the body through these openings, their ends depending and being looped as shown at 12, to form stir-

2
rups. Knots 13 in the stirrup ropes immediately adjacent the two sides of the body keep the ropes in place.

6 Figs. 1 and 2 show the toy suspended from and in an A-frame 14, which may be of either metal or wood. The body is suspended from the longitudinal top member 15 of this frame by three ropes 16, the upper ends of which are tied or otherwise fastened 10 to the top member and kept from longitudinal movement thereon by grooves or ridges 17. The ropes may be provided with adjustment clamps 18, so that the ropes can be lengthened and shortened.

15 In the case of the use of ropes used as suspension members, the lower parts of the ropes pass downward through openings in the top and bottom of the body, and their lower ends are tied to plates which bear up- 20 on the bottom of the body and prevent the ropes from pulling through. Chains may be also used as indicated at 16^a in Fig. 5, in which case the lower end of such chain will be attached to an eye 19 on the top of 25 the body.

The two forward ropes or cables 16 are passed through openings in, or otherwise engaged with, the noses of the heads 3, which prevents the hobby-horse from tilt- 30 ing laterally when the children are on it. Rope loops 20 threaded across through the noses serve as reins.

Fig. 3 shows suspension ropes 16^b converging upward and united at a central point,

enabling the hobby-horse to be hung from a 35 tree.

The device may be also made as a single hobby-horse, but the double form is preferred and can be made quite inexpensively.

It is advantageous to mount a running- 40 board 21 at the inner side of one side of the frame at a suitable level, so that a child may step onto it in order to mount the horse. A rope 22 fastened to the upper forward corner of the frame enables the child to 45 set the hobby-horse in motion by pulling.

I claim:

1. A swinging hobby-horse comprising an elongated barrel-like body having the effigy of an animal head rising therefrom, with 50 means for suspending the body in a frame or from other overhead support, to swing lengthwise, a rope which passes upward from the body and forms part of the suspension means being engaged with the forward part of the animal head to prevent lateral tipping.

2. A swinging hobby-horse comprising a body having an effigy of an animal head rising therefrom, and means for suspending 60 the body to swing lengthwise, the suspension means including a rope or cable which is secured at its lower end to the body and above the body engages the forward part of the head so as to prevent lateral tip- 65 ping.

HARRIETTE ENSLEY HODGSON.
